We claim the ornamental design for a light guide plate, as shown and described.

DESCRIPTION

FIG. 1 is a perspective view of a light guide plate showing our design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a perspective view of the light guide plate in a first state of use for reference.

FIG. 9 is a front view of the light guide plate in the first state of use in FIG. 8.

FIG. 10 is a perspective view of the light guide plate in a second state of use for reference; and,

FIG. 11 is a perspective view of the light guide plate in a third state of use for reference.

The broken lines in the drawings are employed to show unclaimed portions of the light guide plate, and form no part of the claimed design.
